UNITED STATES PATENT OFFICE.

ARTHUR SHERIDAN HUGHES, OF MANSFIELD, OHIO.

TAIL GATE.

Application filed September 16, 1925, Serial No. 56,673. Renewed October 4, 1926.

This invention relates to a tail gate for express bodies, so arranged that it may be opened either at the bottom or the top.

The object of the invention is to provide a simple and practical device, which is easily manipulated for controlling the movement of the gate, and which may be operatively connected to an ordinary type of express body having a downwardly opening tail gate, and without any alteration in the latter convert it into a double-acting gate, so that in handling such materials as coal, sand, cinders, crushed stone and the like, the contents of the body may be discharged underneath the gate, instead of burying the same.

The specific construction of the invention and its advantages will be more fully explained in connection with the accompanying drawings, which illustrate one embodiment thereof.

In the drawings:

Figure 1 is a rear elevation of a body equipped with my invention, and showing the tail gate closed and locked.

Figure 2 is a similar view, partly in section, showing the gate unlocked at the bottom and ready to open.

Figure 3 is a side elevation of the rear end of the body with the parts in the position shown in Figure 1.

Figure 4 is a similar view with the parts in the position shown in Figure 2.

Figure 5 is a vertical longitudinal section showing the gate opened from the top.

Figure 6 is a side elevation showing the body in dumping position with the gate opened at the bottom.

Figure 7 is a vertical longitudinal section showing the gate closed and locked.

Figure 8 is a detail view of the means for fastening the hinge rod.

Figure 9 is a perspective view of the attachment.

The invention is adapted to be used in connection with an express body 10, of common construction, having at its rear end a U-shaped rail 11, with a plurality of rearwardly projecting eyes 12. The tail gate 13 has corresponding eyes 14 projecting downwardly from its lower edge, and ordinarily connected to the eyes 12 by a hinge rod, about which the tail gate swings when it is opened. This is the construction employed on the Ford body. Rearwardly projecting eyes 15 are secured to the upper ends of the U-shaped member 11, and connected to these

eyes are chain links 16, which are adapted to receive lugs 17, projecting from the upper corners of the tail gate to lock the latter in closed position. The links 16 are held on the lugs 17 by chain hooks 18, which are hooked into the perforated ends of the lugs. The hooks 18 are carried on the ends of chains 19, the other ends of which are connected to the links 16. When the hooks 18 are removed from the lugs 17, the latter may be disengaged from the links 16, and the tail gate swung downwardly to a substantially horizontal position. The extent of this movement is limited by the length of the chains 19, the hooks 18 being again inserted in the lugs 17 after the latter are disengaged from the links 16.

In converting a tail gate of this construction into a double-acting gate, the hinge rod, which usually connects the eyes 12 and 14, is removed, and the attachment shown in Figure 9 is connected with the two outer eyes 12 but the hinge rod is used as a part of this attachment. This attachment comprises a bar 20, formed at one end with a laterally extending lug 21, and having near its other end a similarly disposed lug 22, which is removably secured by bolts 23, or the like. Pins 24 are permanently secured to the lugs 21 and 22 respectively, and are adapted to engage the two outer eyes 12, but are not long enough to engage the eyes 14. A rod 25 which may be the former hinge rod has one end mounted in the lug 21, and the other end connected to a lateral projection 26 on the lug 22 by means of a cotter pin 27, or the like. A sleeve 28 is slidably mounted on the rod 25, and is formed with a finger 29 adapted to be moved into engagement with the central eyes 12 and 14, to form a hinge pin about which the tail gate pivots when it is moved downwardly. A laterally projecting finger 30 is secured to the sleeve 28 for convenience in shifting the same.

When the tail gate is closed and locked, as shown in Figures 1 and 3, the finger 29 is moved into engagement with the central eyes 12 and 14, and the top of the gate is held by the links 16, which engage the lugs 17. The bar 20 is swung upwardly about the pins constituting the axis, so that the end portions of the rod 25 engage the outer faces of the two outer eyes 14, and aid in holding the lower side of the gate firmly closed. One end of the bar 20 is turned laterally, as shown at 31, and terminates in an ear 32

adapted to be sprung so as to engage in front of the U-shaped member 11 to hold the bar in this position. When it is desired to open the gate at the bottom, the arm 31 may be sprung sufficiently to permit the ear 32 to pass the rail 11. The bar 20 is then swung to the position shown in Figures 2 and 4, thus releasing the bar from the two outer ears 14. The sleeve 28 and finger 29 are then 10 moved longitudinally to release the central eye 14, so that the gate may swing to the position shown in Figure 6. When it is desired to open the gate from the top, the bar 20 is also swung to the position shown in Figures 2 and 4, and the lugs 17 are released. The gate may then be swung to the position shown in Figure 5, in which position the finger 29 forms a hinge pin for the central eye 14, and the two outer eyes 14 ride on the 20 end portions of the rod 25, and aid in supporting the outer ends of the gate.

From the foregoing description, it will be seen that I have provided a simple attachment, which will convert the ordinary 25 downwardly opening tail gate of a Ford express body into a double-acting gate. The attachment may be very easily applied to the express body, merely by removing the cotter pin 27. While I have shown and described 30 in detail the specific construction of the device as at present constructed, it is apparent that many modifications may be made therein without departing from the spirit of the invention or sacrificing any of its advantages. It is my purpose, therefore, to include all such modifications within the scope of the appended claims.

What is claimed is:—

1. The herein described attachment, comprising a bar formed at one end with a laterally extending lug and having near its other end a similar lug, fixed inwardly extending hinge pins carried by said lugs, a longitudinally arranged rod carried by the 45 bar and mounted in said lugs, and a sleeve slidably mounted on the rod and provided with a locking finger forming a hinge pin in longitudinal alinement with the other hinge pins.

2. The herein described attachment, comprising a bar formed at one end with a laterally extending lug and having near its other end a similar lug, fixed inwardly extending hinge pins carried by said lugs, a 55 longitudinally arranged rod carried by the bar and mounted in said lugs, and a sleeve slidably mounted on the rod and provided with a locking finger forming a hinge pin in longitudinal alinement with the other hinge pins, said bar having one end turned laterally and provided with an ear and constituting an operating and locking means for said bar.

3. The combination with a body having 60 at its rear a plurality of rearwardly pro-

jecting eyes, a tail gate having eyes projecting downwardly from its lower edge and adapted to register with the eyes on the body, means for hanging the gate from the body at the top so as to swing outwardly and upwardly away from the bottom, and separate means for pivotally connecting the gate to the body at the bottom so that the gate may swing outwardly from the body, said last means consisting of a bar pivotally 70 connected to the eyes on the body, a rod carried by the bar, and a slideable means mounted on the rod and adapted to engage one of the eyes on the body with one of the eyes on the gate to pivotally connect the gate and 75 body together at the bottom.

4. In combination with a body, a tail gate, means for hanging the gate from the top of the body so as to swing outwardly from the bottom, and means for pivotally connecting 85 the gate to the body at the bottom, said last means including a bar pivotally connected to the body, a rod carried by the bar, and slideable means mounted on the rod for engaging the gate, said slideable means forming a 90 pivotal connection between the gate and the body at the bottom.

5. In combination with a body having at its rear a U-shaped rail provided with a plurality of eyes, a tail gate having eyes projecting downwardly from its lower edge and adapted to register with the eyes on the rail, a bar pivotally connected to the eyes on the rail, a rod carried by the bar, and slideable means mounted on the rod for engaging 95 one of the eyes on the rail and on the gate to pivotally connect the gate to the rail so as to swing downwardly.

6. In combination with a body having at its rear a U-shaped rail provided with a 105 plurality of eyes, a tail gate having eyes projecting downwardly from its lower edge and adapted to register with the eyes on the rail, means for connecting the U-shaped rail to the tail gate at the upper end, so as to swing outwardly from the bottom, and means for pivotally connecting the gate to the eyes on the rail comprising a bar pivotally connected at its ends to the eyes on the rail, a rod carried by the bar, means mounted on 110 the rod for engaging one of the eyes on the rail with one of the eyes on the gate, so as to constitute a hinge about which the gate is 115 swung.

7. In combination with a body having at 120 its rear a U-shaped rail provided with a plurality of eyes, a tail gate having eyes projecting downwardly from its lower edge and adapted to register with the eyes on the rail, means for connecting the U-shaped rail to 125 the tail gate at the upper end, so as to swing outwardly from the bottom, and means for pivotally connecting the gate to the eyes on the rail comprising a bar pivotally connected at its ends to the eyes on the rail, a 130

rod carried by the bar, means mounted on the rod for engaging one of the eyes on the rail with one of the eyes on the gate, so as to constitute a hinge about which the gate is 5 swung, one end of said bar being turned laterally and formed with an ear adapted to be sprung in front of the **U**-shaped rail to hold the bar in its adjusted position.

8. In combination with a body having at 10 its rear a **U**-shaped rail provided with a plurality of eyes, a tail gate having eyes projecting downwardly from its lower edge and adapted to register with the eyes on the body, means for hingedly connecting the **U**- 15 shaped rail to the tail gate at the upper end, means for limiting the downward movement of the tail gate, a bar pivotally connected to the eyes on the body, a rod carried by the bar, and means mounted on the rod for 20 engaging registering eyes on the body and

on the gate to pivotally connect the gate so as to swing downwardly.

9. In combination with a body having at its rear a **U**-shaped rail provided with a plurality of eyes, a tail gate having eyes projecting downwardly from its lower edge and registering with the eyes of said rail, means for connecting the **U**-shaped rail to the tail gate at the top, a bar having lugs near the opposite ends, pins carried by the lugs and 25 adapted to pivot in the end eyes of the rail, a rod carried by the bar, a sleeve slidable on said rod and provided with a finger adapted to engage registering eyes on the rail and tail gate and form a bottom pivot for the gate, 30 and means on the bar for turning the same about its pivot.

In testimony, that I claim the foregoing as my own, I have hereto affixed my signature.

ARTHUR SHERIDAN HUGHES.
